UNITED STATES PATENT OFFICE.

ISAAC S. BUNNELL, OF CARBONDALE, PENNSYLVANIA.

IMPROVEMENT IN BREAD-CUTTERS.

Specification forming part of Letters Patent No. 119,569, dated October 3, 1871.

To all whom it may concern:

Be it known that I, ISAAC S. BUNNELL, of Carbondale, in the county of Luzerne and State of Pennsylvania, have invented a new and Improved Cutter for Bread, &c.; and I do hereby declare that the following is a full, clear, and exact description thereof, which will enable others skilled in the art to make and use the same, reference being had to the accompanying drawing forming a part of this specification, in which—

Figure 1 represents an end elevation of my improved cutter for bread, &c. Fig. 2 is a vertical longitudinal section of the same taken on the plane of the line *c c*, Fig. 1.

Similar letters of reference indicate corresponding parts.

This invention relates to a new machine for cutting bread; and consists in a new manner of hanging the knife so that it will be supported at both ends and moved with a slight drawing motion to insure a powerful cut.

A in the drawing represents the knife pivoted at one end to a straight lever, B, and at the other end to an elbow-lever, C. The lever B is at *a*, pivoted to the supporting-frame. The lever C is pivoted to said frame at *b*, under the middle of the knife. The frame D contains the legs *d d*, a horizontal bar, *e*, and a vertical projection, *f*, all cast in one piece. The ear *g*, receiving the pivot *b*, is underneath the bar *e*, and somewhat set

back of its face, so that the horizontal arm *h* of the elbow-lever C will strike against the lower edge of *e* (see Fig. 2) to arrest the knife when swung up and prevent its being raised more than necessary. *E* is a box or support for the matter to be cut, secured at one end upon the bar *e* and to the projections *f*, and at the other end to an additional leg, *i*.

The knife when swung down by a person holding it by the handle *j* will descend at the handle end slightly faster than at the other end, thus producing a drawing cut.

The device is adapted to cutting hay, straw, &c., without change in the arrangement of its working parts.

Having thus described my invention, what I claim as new, and desire to secure by Letters Patent, is—

The combination, as described, with knife A, of the straight lever B and nearly right-angled lever C, each pivoted at opposite ends of the knife, and also to the frame, for the purpose of giving a backwardly-drawing cut to the knife from heel to point when forced down.

The above specification of my invention signed by me this 27th day of July, 1871.

ISAAC S. BUNNELL.
